Application March 31, 1932, Serial No. 602,373
Renewed February 25, 1935

18 Claims. (Cl. 89—28)

1

This invention relates in general to director or salvo firing systems for ordnance and in particular to a firing mechanism to be used with such systems for firing ordinance mounted on a ship or other angularly moving platform.

In salvo firing all of the guns of a battery are fired simultaneously at a predetermined point in the roll of the ship. This is frequently accomplished by the use of a firing mechanism which can be set to close the firing circuit at a predetermined point in the ship's roll and which is provided with means for closing the firing circuit when this predetermined point in the ship's roll is reached. Due to the fact that there is an appreciable lapse of time between the instant the firing circuit is closed and the instant the projectile leaves the gun's muzzle and that during this time the gun is carried out of the position it occupied at the instant the firing circuit was closed, the firing circuit must be closed at a point in the ship's roll in advance of the point at which the projectile must leave the gun in order to hit the target.

It has been proposed to take care of this advance time interval by so proportioning the parts of the firing mechanism that the circuit will be closed at a fixed angular distance in advance of the position in the roll of the ship at which the projectile should leave the gun's muzzle in order that it hit the target. As the speed of roll of the ship is different at every point in the roll this expedient will at best give a correct advance time interval at but one point in the roll and at all other points will give an advance time interval which is either too great or too small.

A firing mechanism has also been proposed which maintains the advance time interval at a constant and proper value at all points in the roll of the ship by varying, in accordance with the velocity of the roll of the ship, the angular distance by which the closing of the firing circuit is advanced. This is accomplished by the use of a gyroscopic means to advance the closing point of the firing circuit in proportion to the velocity of the roll, which gyroscopic means is separate from and in addition to the gyroscopic means used to move the firing circuit closing member relative to the ship. The additional gyroscopic means renders the mechanism more delicate and introduces a source of error which may at times be greater than the error which it is intended to correct, for in order to obtain the desired results it will be necessary to maintain two gyroscopes level by compensating for the effect of stray producing influences to which they are subject.

2

This invention is in the nature of an improvement over the above mentioned firing mechanisms and has for an object a firing mechanism of simple, rugged construction having a minimum of delicate, adjustable parts, in which a single gyroscope is used to move the firing circuit closing member relative to the ship as the ship rolls and to advance the point of closing of the firing circuit proportional to the velocity of roll of the ship.

In accordance with the invention the firing mechanism comprises a single gyroscopic unit and follow-up mechanism therefor which operates suitable mechanism for continuously determining the level angle, that is, the angle which the ship's deck makes with the horizontal in the plane of the line of sight, and the velocity of roll of the ship. The value of the level angle is continuously applied to an input member of a computing device which has another input member operatively connected to the output member of a second computing device whereat the director correction, that is, the angle which the ship's deck must make with the horizontal in the plane of the line of sight at the time the projectile leaves the gun's muzzle in order to hit the target, is computed from the arbitrary gun elevation, that is, the gun elevation arbitrarily chosen by the operator who determines the point in the ship's roll at which the projectile is to leave the gun's muzzle, corrected for cross roll if desired, and the sight depression, that is, the angle the gun must make with the horizontal at the time the projectile leaves the gun's muzzle in order to hit the target.

The computing device first mentioned serves to continuously subtract the level angle from the director correction and operates from its output a firing switch in accordance with this difference.

40 The switch is so arranged that, with zero correction for advance time interval, it will close the firing circuit when the level angle is equal to the director correction. To take care of the advance time interval due to the velocity of roll, the switch is provided with a device operatively connected to the mechanism for continuously determining the velocity of roll, which continuously adjusts the firing switch so that the firing circuit will be closed at an angular distance in advance of the point in the roll of the ship at which the shell is to leave the gun's muzzle, proportional to the velocity of the roll. By this arrangement the advance time interval is constant for all points in the roll. The firing switch adjusting device is so

arranged that if it is desired it may be locked in any position of adjustment.

The particular nature of the invention as well as other objects and advantages thereof will appear most clearly from a description of a preferred embodiment thereof as shown in the accompanying drawings, in which,

Fig. 1 is a schematic representation of the entire firing mechanism, the firing switch being shown in sufficient detail to bring out its novel construction;

Fig. 2 is a part sectional end view of the circuit closing switch of Fig. 1 with the parts thereof arranged in the firing circuit closing position; and

Fig. 3 is a view similar to that of Fig. 2 but shows the parts of the switch in an open circuit position.

When using the firing mechanism illustrated in Fig. 1 of the drawings to fire guns mounted on a ship or other moving platform, the sight depression and the arbitrary gun elevation angle, corrected for cross-level if desired, are transmitted by means not shown, to the operator in charge of the firing mechanism. The operator will turn hand crank 1 mounted on shaft 2 until the value of the gun elevation angle is indicated on dial 3 opposite fixed index 4, dial 3 being connected to shaft 2 through gear 5. The rotation of shaft 2 is transmitted through gears 6 and 7 to side 8' of a differential 8, and since side 8'' can at this time be considered as fixed, center 8''', and shaft 9 upon which it is fixed will be rotated in accordance with the input at crank 1. The operator will then turn crank 10, mounted on shaft 11 until the value of the sight depression is indicated on dial 12 opposite fixed pointer 13, dial 12 being connected to shaft 11 through gear 14. The rotation of shaft 11 is transmitted through gears 15 and 16 to side 8'' of differential 8, and since 8' can now be considered as fixed, center 8''', and shaft 9 upon which it is fixed will be rotated in accordance with the input at crank 10, but the direction of rotation will be such as to subtract the value of this input from the value of the input at crank 1. The net rotation of shaft 9 will thus be equal to the director correction. Gear 17 mounted on shaft 9 rotates gear 18, shaft 19, and dial 20 at which the value of the director correction may be read opposite the index 21. Shaft 9 through gears 22 and 23 also rotates side 24' of differential 24. The rotation of side 24', since at this time side 24'' can be considered as fixed against motion, causes the rotation of center 24''' and shaft 25 upon which it is mounted.

The level angle and the speed of the roll are continuously determined from a suitable gyroscope 26 mounted by trunnions in a gimbal ring 27 carried on trunnions 28 and 29 supported in suitable bearings fixed to the base on which the gyroscope is embodied. It will be understood that the trunnions of the gyroscope are maintained in the vertical plane of the line of sight by suitable training means. The relative motion between the ship and the gyroscope and its gimbal ring is transmitted through shaft 30, which is formed as an extension of the trunnion 29, to a contact arm 31 electrically insulated from shaft 30 by means of an insulation strip 32. A roller 33 is carried at the upper end of arm 31 and is connected to one side of an electrical supply 34 through a conductor 35. Roller 33 is adapted to contact with the under side of an arcuate commutator 36 which comprises an upper T-like portion 37 made of insulation material and lower

metallic contacts 38 and 39. The vertical portion of the T extends between the contacts 38 and 39 and is of sufficient width to not only electrically separate them but also to keep roller 33 out of contact with these contacts when it is in the normal or central position. Contact members 38 and 39 are connected through conductors 40 and 41 respectively to terminals of a reversing servo-motor 42. The common terminal of this motor is connected through conductor 43 to the second side of the electrical supply 34. Commutator 36 is carried by arms 44 which form offset extensions of worm gear sector 45 and is insulated therefrom by suitable insulation inserts. Worm gear sector 45 is carried by shaft 46 mounted for rotation in bearings 47 and 48, fixed relative to the trunnions for ring 27, and meshes with worm 49 carried by shaft 50 of the motor 42.

As the ship rolls gyroscope 26 and its gimbal ring 27 will move relative to the deck of the ship through an angle equal to the angle of roll and at a velocity equal to the velocity of roll. This motion is transmitted through shaft 30 and arm 31 to roller 33 and carries it from its normal position on the insulation strip between contact members 38 and 39 to one or the other of these members, depending on the direction of roll, thereby closing the circuit of servo-motor 42 to cause it to rotate shaft 50 and worm 49 in the direction corresponding to the direction of roll of the ship. Rotation of worm 49 will carry worm gear sector 45 and commutator 36 through an angle equal to that through which arm 31 has been carried, thus bringing the insulation strip 37 again into contact with roller 33 to open the circuit of the servo-motor. As the angular displacement of arm 31 is increased by movement of the gyroscope and its gimbal ring the cycle of operations is repeated. The follow-up system just described repeats accurately each increment of movement of the gyroscope and its gimbal ring as such movement occurs and produces a rotation of shaft 50 which although actually intermittent or variable is in effect continuous insofar as its effect upon the operation of the mechanism is concerned. The instantaneous value of the level angle may be read on dial 51 opposite index 52, dial 51 rotating with shaft 50 through gear 51'.

The instantaneous value of the level angle is transmitted by the rotation of shaft 50 through gears 53, 54, shaft 55, gears 56, 57, shaft 58 and gears 59, 60 to side 24'' of differential 24. At this time side 24' may be considered as fixed against motion and the rotation of side 24'' will cause a corresponding rotation of center 24''' and shaft 25. The rotation of shaft 25 is in a direction relative to the rotations of the sides 24' and 24'' so that the net rotation of shaft 25 is equal to the difference of the rotations of the sides. Shaft 25 carries gear 61 which rotates dial 62 to indicate opposite index 63 the instantaneous value of the difference between the director correction and the level angle.

At the end of shaft 25 is mounted a pinion 64 which transmits the rotation of shaft 25 to a gear wheel 65 fixed on shaft 66 to rotate this shaft in accordance with the instantaneous value of the difference between the director correction and the level angle. Shaft 66 projects through frame member 67 fastened to bed plate 68 of the switch mechanism and carries for rotation therewith a spider 69 and a fine control cam 70. The shape of cam 70 is in part that of a spiral. A double gear member comprising gears 71 and 72 having

a like number of teeth but of slightly different pitch is mounted for rotation on one of the arms of spider 69. A weight 73 is carried on the other arm to counterbalance the weight of the double gear. Gear 71 of the double gear meshes with a stationary gear 74 fixed to the frame member 67 by means of a screw 75. Gear 72 of the double gear meshes with a gear 76 concentric with shaft 66 and freely rotatable thereon. Gear 76 is provided with a greater number of teeth than gear 74 and rotates about shaft 66 when the double gear 71, 72, walks around gear 74 due to the rotation of spider 69. Since the distance between the centers of the pair of gears 71 and 74 is the same as between the centers of the pair of gears 72 and 76, and since gear 76 has a greater number of teeth than gear 74 it is necessary to make the diametrical pitch of gears 72 and 76 slightly greater than of gears 71 and 74. The amount of rotation of gear 76 for each revolution of shaft 66 is equal to the number of teeth which gear 76 has in excess of the number of teeth of gear 74 divided by the number of teeth of gear 76. Gear 76 is provided with a female threaded cylindrical extension which screws onto a male threaded cylindrical member forming an integral part of a coarse control cam 77. Cam 77 is concentric with shaft 66 and freely rotatable thereon. The periphery of cam 77 is a true circle with the exception of an accurate notched portion 78 the length of which should not exceed the degrees of arc through which cam 77 moves during one revolution of cam 70.

Fine control cam 70 and coarse control cam 77 contact with cam followers 79 and 80 respectively carried for rotation by a shaft 81 whose ends are fixed in follower arms 82 and 83. The follower arms are held in fixed spaced relation at their lower ends by a pin 84 and are fulcrumed on a shaft 85 fixed in frame members 67 and 86. A spring 87 connects pin 84 to an anchor 88 and forces the cam followers into contact with their respective cams. At the upper end of the follower arms are mounted insulation blocks 89 between which is mounted a metallic member 90 which carries the firing contact element 91. Member 90 is slotted longitudinally and is provided with a screw 92 for fixing the firing contact element in any position of adjustment. A conductor 93 connects member 90 with one side of the firing circuit. Contact element 91 will move about shaft 85 as cam followers 79 and 80 follow cams 70 and 77.

Contact arms 94 and 95 straddle the follower arms 82 and 83 and are pivoted at their lower ends on shaft 96 fixed to frame members 67 and 86. Somewhat above the middle of the contact arms is mounted an insulation block 97 which carries a metallic member 98 having its upper portion cut away in the form of a semicircle to provide two arms. These arms are suitably perforated and act as bearings for the trunnions of a gimbal ring 99 in which is pivotally mounted the contact element 100. A conductor 101 connects member 98 and contact element 100 to the firing circuit. Because of the form of suspension employed contact element 100 automatically adjusts itself to make a good contact with contact element 91 in spite of the wear or adjustment of either of the contact elements.

Contact arms 94, 95 are fixed in spaced relation at their upper ends by a block 102 having a center bore 103 in which freely moves the end of pin 104. The other end of pin 104 takes the form of a screw 105 and is in screw threaded engagement 76 have carried notch 78 out of line with cam fol-

with a frame member 106. A compression spring 107 encircles pin 104 and abuts at its ends against wear washers 108. Spring 107 exerts a constant force in a direction tending to keep block 102 in contact with a cam 109 as best shown in Fig. 3.

Cam 109 which is fixed to a shaft 110 is of spiral form, its size and characteristics being dependent upon the size and characteristics of the spiral portions of fine control cam 70. Shaft 110 extends through frame member 86 and has fixed to its outer portion a bobbin dial 111 suitably graduated to indicate the advance fire adjustment in minutes of roll opposite line 112 on an index plate 113 which fits between the discs of the bobbin dial 111. A screw 114 terminating in a knurled head passes through a smooth hole in plate 113 and is adapted to be screwed into a tapped hole in frame member 86 to bring the index plate 113 into contact with the back disc of the bobbin dial 111 to fix the dial, shaft 110 and cam 109 in any desired position of adjustment. Pins 115 fastened to frame member 86 extend through holes in the index plate 113 and serve to keep it and line 112 fixed as an index mark for the graduated disc of the bobbin dial 111.

Shaft 110 terminates at its other end in a crank 116 which is connected by means of a link 117 to the end 118 of a bell crank lever 119 pivoted by means of pin 120, the support for which is not shown. The other end of bell crank 119 terminates in a finger 121 which fits in an annular groove 122 in a collar 123. Collar 123 is slidably mounted on a shaft 124 and is pivotally connected to links 125 which are in turn pivotally connected to arms 126 carrying fixed at their lower ends balls 127. Arms 126 are pivoted at their upper ends in a collar 126 secured on shaft 124. A compression spring surrounds shaft 124 and rests against collars 123 and 126. A gear 129 mounted at the lower end of shaft 124 meshes with gear 53 and transmits the rotation of shaft 50 to shaft 124. Arms 126 and balls 127 will turn with shaft 124 and centrifugal force acting on balls 127 will cause them to fly out and react against spring 128. The outward movement of balls 127 will carry collar 123 up and down shaft 124 as the speed of rotation of shaft 124 varies. The position of collar 123 on shaft 124 will at any time correspond to the velocity of roll of the ship. The movement of collar 123 is transmitted through bell crank 119, link 117 and crank 116 to shaft 110. Cam 109 is thereby rotated to change the distance between shaft 110 and block 102 to correspond with the velocity of roll at any instant. This will also move contact 100 away from its zero position, the position shown in Fig. 3, in proportion to the velocity of the roll.

For the purpose of explaining the manner of operation of the switch we will assume that its parts are positioned as shown in Fig. 2, and that there is no roll. As the operator computes the value of the director correction by rotation of hand cranks 1 and 10, as previously explained, shaft 25 will rotate to cause a rotation of fine and coarse cams 78 and 77, as previously explained to position them in accordance with the computed value of the director correction. As cam 70 begins to rotate it will offer an increasing radius to the contact of cam follower 79 and thus will carry it as well as follower arms 82 and 83 and contact 91 away from contact 100. As the rotation continues cam 70 will finally offer its greatest radius to the contact of cam follower 79. The rotation of coarse cam 77 during this time will

lower 80. With fine cam 70 in the position just mentioned cam follower 80 will be in contact with the periphery of coarse cam 77. From this point on coarse cam 77 will exercise control and will maintain contact 91 in the position shown in Fig. 3.

As the ship begins to roll and the level angle and velocity of the roll are determined, as previously described, shaft 25 will rotate in accordance with the difference of the director correction value and the level angle and will rotate fine and coarse cams 70 and 77. As the level angle approaches to within a few degrees of the value of the director correction, notch 78 will be substantially in line with cam follower 80 so that fine cam 70 will again control the movement of cam follower 79, follower arms 82 and 83, and contact 91. As the ship rolls cam 109 will be moved, in the manner previously described, to position contact 100 away from the position it occupies in Fig. 3 in proportion to the velocity of the roll. As the ship continues to roll the rotation of fine and coarse cams 70 and 77 will continue with cam 70 offering a continuously diminishing radius to the contact of cam follower 79.

When cam follower 79 is in contact with a radius of cam 70 which is more than the minimum radius of cam 70 by an amount equivalent to the distance that contact 100 has been moved away from the position it occupies in Fig. 3, contacts 100 and 91 will come together to close the firing circuit. The cams are so proportioned that the angular distance between this point on the periphery of cam 70 and the point at the minimum radius expressed in minutes of arc represents the angle of advance expressed in minutes of arc. From the previous description it is evident that the angle of advance is always proportional to the velocity of roll.

If it should become necessary or desirable, the described mechanism may be set to fire the guns for a period of time at a fixed angle of advance. This is accomplished by rotating bobbin dial 111 until the desired value of the angle of advance is read opposite line 112 on brake plate 113 and then securing the dial in position by screwing screw 114 into frame member 86. By so doing shaft 110, cam 109, crank 116, link 117, bell crank 119 and finger 120 are fixed in position and prevent collar 123 and balls 127 from moving up and down shaft 124 as the velocity of the roll changes. The level angle solving mechanism will not be affected by thus fixing the position of cam 109 and will continue to function as previously described.

While a preferred embodiment has been shown and described, it is understood that the invention may be embodied in other forms, and various changes may be made without departing from its principle as defined in the appended claims.

We claim:

1. In a firing mechanism for a gun mounted on an angularly movable platform, the combination of a gyroscope mounted on the platform to measure the angular motion of the platform relative to a fixed datum, a firing switch, a computing mechanism for determining the angle of the platform relative to a horizontal datum with respect to which the gun is angularly set to be fired, a switch actuating means operatively connected to said computing mechanism adapted to be set to close the switch at the computed value of said angle, means operatively connecting said switch actuating means with the gyroscope, and means operated by said gyroscope for advancing the closing of the switch in accordance with the velocity of the angular movement of the platform.
2. In a firing mechanism for a gun mounted on an angularly movable platform, the combination of a gyroscope mounted on said platform to measure the angular motion of the platform relative to a fixed datum, means controlled by the gyroscope for continuously determining the value of the angle which the platform makes with the datum, independently operable calculating means for determining a particular angle of the platform relative to a horizontal datum with respect to which the guns are angularly set to be fired, a computing device operated by said last mentioned means and said gyroscope controlled means for combining the values of said angles, a firing switch, actuating means therefor operatively connected to said computing device, whereby the switch will be closed when the two angles are equal, and means operated by the gyroscope for advancing the closing of the switch in proportion to the velocity of angular movement of the platform.
3. In a firing mechanism for a gun mounted on an angularly movable platform, the combination of a gyroscope mounted on said platform to measure the angular motion of the platform relative to a fixed datum, means controlled by the gyroscope for continuously determining the value of the angle which the platform makes with the datum, an independently operable computing device operated in accordance with firing data for computing a particular angle of the platform relative to a horizontal datum with respect to which the gun is angularly set to be fired, a second computing device operated by said first computing device and said gyroscope controlled angle determining means to compute the difference of said angles, a firing switch, an actuating means therefor operated by said second computing device adapted to close said switch when the difference of said angles is zero, and means operated by the gyroscope to advance the closing of the switch in proportion to the velocity of angular movement of the platform.
4. In a firing mechanism for a gun mounted on an angularly movable platform, the combination of a gyroscope mounted on the platform to measure the angular movement of the platform relative to a fixed datum, means controlled by the gyroscope for continuously determining the value of the angle which the platform makes with the datum, means independently operable in accordance with firing data for determining the particular angle of the platform relative to the datum at which the gun is to be fired, a differential having two input elements and an output element, one of the input elements being operatively connected to said first means and the other input element being operatively connected to said second means, a switch, actuating means therefor operatively connected to the output element of said differential and arranged to close the switch when the angle determined by the first means is equal to the angle determined by the second means, means for advancing the closing of the switch in proportion to the velocity of the angular movement of the platform, and means operatively connecting said last named means to the gyroscope.
5. In a firing mechanism for a gun mounted on an angularly movable platform, the combination of a gyroscope mounted on the platform to measure the angular movement of the platform rela-

tive to a fixed datum, a level angle determining means operated by said gyroscope; a director correction determining means; means for combining said angles, a switch, means actuated by said combining means adapted to close said switch when the level angle equals the director correction, and means controlled by said gyroscope and adapted to advance the closing of the switch in accordance with the velocity of the movement of the platform.

6. In a firing switch, a pair of relatively movable circuit closing elements, one of said elements being movable to change the circuit closing position of said elements, means for moving said one element, means for urging the other element of the pair into circuit closing relation with said one element, and means for controlling the movement of said other element, said control means including a pair of correlated rotatable cams, one of said cams serving to hold said other element in a fixed position during a plurality of revolutions of the other of said cams.

7. In a firing switch, a pair of relatively movable circuit closing contacts, a pair of spaced contact arms carrying between them one of said contacts for movement therewith, means to move said arms to position said contact as desired, a pair of spaced follower arms carrying between them the other of said contacts for movement therewith, means effective on said follower arms for urging said other contact into circuit closing relation with said one contact, a pair of followers mounted between said follower arms, a rotatable shaft, a pair of cams concentric therewith adapted to engage said followers, a speed reducing means connecting one of said cams with said shaft, the other of said cams being connected to said shaft to rotate therewith, said one cam being adapted to restrain said other contact from movement while its periphery engages its respective cam follower, said other cam being adapted to engage its follower when said other cam is out of engagement with its follower to allow said other contact to come into circuit closing relation with said one contact.

8. In a firing switch, a pair of relatively movable circuit closing contacts, the position of one of said contacts determining the circuit closing position of the contacts, a pair of contact arms mounting said one contact between them, a cam follower member connecting said contact arms at their upper ends, means effective on said follower member for urging said one contact toward the other of said contacts, a rotatable shaft, a cam mounted thereon adapted to engage said follower member to restrain its movement, means on said shaft for indicating the displacements of the follower member whereby said one contact may be definitely positioned by the rotation of said shaft, means to fix said shaft in any desired position, and means for controlling the movement of said other contact.

9. A firing switch comprising a pair of circuit closing elements individually mounted for separate movement, yielding means continuously urging one of the elements of the pair toward a circuit closing relation with the other element thereof, controlling means comprising a plurality of members operable to respectively exercise a fine and a coarse control of said one element and movable into mutual correlations in one of which the coarse controlling member maintains said one element separated from the other element, and in another correlation wherein the fine controlling member alone controls said one element

and with said yielding means effects its displacement into said circuit closing relation with the other element of the pair, and means to move said other element of the pair to change the circuit closing relation of said elements.

10. In apparatus for automatically operating a contacting device mounted on an angularly moving platform, the combination of a pair of relatively movable members for controlling the device, a gyroscope mounted on the platform to move relative thereto as the platform moves, a follow-up mechanism actuated in accordance with the relative movement of the said gyroscope, means connecting one of said members with the follow-up mechanism to control the movement of said member in accordance with the relative movement of the gyroscope, means continuously operated by said follow-up mechanism in response to the instantaneous velocity of the relative movement of the gyroscope, and means continuously operated by said velocity responsive means to position the second member of the pair so as to variably advance the operation of the contacting device as a function of the instantaneous velocity of the relative movement of the gyroscope.

11. In a firing mechanism for a gun mounted on an angularly movable platform, the combination of a gyroscope, mounted on the platform to measure the angular motion of the platform relative to a fixed datum, a firing switch, means to set the switch to close at a desired position of the platform relative to the datum, means actuated by the gyroscope to operate the switch when the platform attains the desired position, speed responsive means continuously operated by the gyroscope, and means continuously actuated by the speed-responsive means to variably advance the closing of the switch in proportion to the instantaneous speed of the angular movement of the platform.

12. In a firing mechanism for a gun mounted on an angularly movable platform, the combination of a gyroscope mounted on the platform to measure the angular motion of the platform relative to a fixed datum, a firing switch, a switch actuating mechanism, means to set said mechanism in accordance with the angle of the platform relative to the datum at which it is desired to operate the switch, means continuously connecting said mechanism to the gyroscope to operate said mechanism in accordance with the movement of the platform relative to the datum, velocity responsive means continuously operated by the gyroscope and means connecting the velocity responsive means to the switch for variably advancing the closing of the switch in proportion to the instantaneous velocity of angular movement of the platform.

13. In a firing mechanism for a gun mounted on an angularly movable platform, the combination of a gyroscope mounted on the platform to measure the angular movement of the platform relative to a fixed datum, a level angle responsive means operated by said gyroscope, a director correction angle setting means, differential means operably connected to compare said last two means, a switch, means actuated by said differential means adapted to close said switch when the level angle equals the director correction angle, and means continuously actuated by the gyroscope to variably advance the closing of the switch as a function of the instantaneous rate of measured angular movement of the platform.

14. In a firing mechanism for a gun mounted

on an angularly movable platform, the combination of a fixed datum establishing means co-acting with the platform to continuously position a member in accordance with the angular motion of the platform relative to the datum, a firing switch, means settable to represent an angular position of the platform relative to the datum at which it is desired to close the switch, means differentially actuated by the member and the settable means to operate the switch when the platform attains the desired position, a device operatively connected with the member and continuously responsive to the instantaneous speed of the angular movement of the platform, and means operatively connecting the speed responsive device to the switch to variably advance the closing point of the switch as a function of said speed.

15. In a firing mechanism for a gun mounted on an angularly movable platform, the combination of an element, controlling means operably connected to the element for moving the element relatively to the platform reversely to the angular movement of the platform and in proportion thereto, whereby the movement of the element measures the angular motion of the platform relative to a fixed datum, a firing switch, means to set the switch to close at a certain position of the platform, means actuated in accordance with the movement of the said controlling means in positioning the element to close the switch when the platform attains the certain position, a device continuously responsive to the instantaneous speed of the angular movement of the platform, and means operatively connecting the speed responsive device to the switch adapted to effect the closing of the switch in advance of the platform attaining the certain position.

16. In a firing mechanism for a gun mounted on an angularly movable platform, the combination of a fixed datum establishing means co-acting with the platform to continuously position a member in accordance with the angular motion of the platform relative to the datum, a firing switch, a switch actuating mechanism, means effective to set said mechanism in accordance with the angle of the platform relative to the datum at which it is desired to close the switch, means operatively connecting said mechanism to said member to thereby operate said mechanism

50

in accordance with the movement of the platform relative to the datum, and speed measuring means continuously operated by the datum establishing means for advancing the closing of the switch in proportion to the instantaneous velocity of angular movement of the platform as represented by movement of the member.

17. In a firing mechanism for a gun mounted on an angularly movable platform, the combination of a firing switch, a member continuously positioned in accordance with the angular movement of the platform, means actuated by said member for closing said switch at a certain angular position attained by the platform during its angular movement, a centrifugal device continuously operable by the member in response to the instantaneous velocity of the angular movement of the platform, and means operatively connecting the velocity response device to the switch to effect a closure thereof in advance of the platform attaining said certain angular position.

18. Automatic means for firing a gun, comprising a gyroscope, a pair of circuit closing contacts, power means controlled by said gyroscope to move one of said contacts toward the circuit closing position according to the angular position of a body upon which said gyroscope is mounted, and means continuously operated by said power means and responsive to the instantaneous velocity of the power means to variably adjust the circuit closing position of the other of said contacts in accordance with the said instantaneous velocity.
